VISE STAND

Filed Feb. 27, 1929

FIG. 1.

FIG. 2.

Inventor

MARTIN BOYD

By Frederick C. Bromley
Attorney.

UNITED STATES PATENT OFFICE

MARTIN BOYD, OF TORONTO, ONTARIO, CANADA, ASSIGNOR TO ERICH SCHLUECKE
AND PAUL ZINK, BOTH OF TORONTO, CANADA

VISE STAND

Application filed February 27, 1929, Serial No. 342,987, and in Canada February 4, 1929.

The invention relates to improvements in portable pipe vise stands as described in the present specification and shown in the accompanying drawings which form part of the 5 same.

The object of the present invention is to provide a stand of this nature in which the weight of the workman using the stand is utilized to anchor it against movement. This 10 is attained by the provision of a platform connected to the base of the stand. A very distinctive feature of the invention is that it is devised to compactly fold for transportation purposes.

15 Referring to the drawings: Figure 1 is a side elevation of the stand showing it erected ready for use.

Figure 2 is a plan view thereof.

Figure 3 is a front elevation of the stand 20 folded for transportation.

In the drawings, the reference numerals 5 and 6 designate a pair of legs rigidly connected at the top to a plate 7 apertured as at 8 in order that it may be attached to the 25 pipe vise which is not shown in the drawings as it does not form a part of the present invention. The legs are constructed of angle iron and extend outwardly and forwardly from the plate 7 in order that they may have 30 a firm footing for supporting the vise.

9 is a prop which is pivoted at its top end as at 10 at a point beneath the table 7 in order that it may be swung outwardly from the legs to form therewith a tripod.

35 11 is a cross bar rigidly connecting the legs 5 and 6 together and positioned slightly above the longitudinal centre thereof. 12 is a hook swingably attached to the crossbar 11 by means of an eye member 13. The downwardly turned end 14 engages in an eye member 15 rigidly secured to the prop 9.

40 From this construction it follows that the hook 12 secures the prop 9 in spaced relation to the legs 5 and 6, but when it is desired 45 to fold the stand the hook 12 is disengaged from the eye member 15 so that the prop may be swung inwardly to lie flat against the legs.

50 16 is the platform consisting of an angle iron frame 17 of which the sides 18, 18' converge on an angle corresponding to the angle

of the legs 5 and 6. Slats 19 extend from side to side of the platform and are spaced apart as shown from an inspection of Figure 2. These slats are rigidly attached to the frame 17 by suitable fastening elements. The ends 55 20, 20' of the frame are pivotally attached to the base of the legs by means of the pintle 21 in order that the platform may be swung upwardly so as to lie flat against the legs when folding the stand. 60

What I claim is:—

1. A stand of the class described, comprising several converging legs, a platform pivoted to two of the legs, said platform having its sides converging at an angle corresponding to the angle of convergence of these two legs for folding against the same. 65

2. A stand of the class described, comprising an apertured plate, a pair of angle-iron legs rigidly affixed thereto and diverging 70 towards their lower ends, a crossbar tying the legs together intermediate of the length, a prop pivoted to the legs in the vicinity of the plate, a hook swingably attached to said crossbar, an eye member secured to the prop 75 for receiving the hook, an angle-iron frame having its sides converging at an angle corresponding to the angle of convergence of the aforesaid legs, slats secured to the frame to compose a platform, and a pintle swingably 80 attaching the ends of the frame to the lower ends of the legs.

Signed at Toronto, Ontario, the 20th day of February, 1929.
